a corporation of New Jersey

Application February 15, 1945, Serial No. 117,984

Term of patent 14 years

(Cl. D1—12)

To all whom it may concern:

Be it known that I, Frederic Carl Reinschield, a citizen of the United States, residing in Andover, county of Essex, and State of Massachusetts, have invented a new, original, and ornamental Design for an Illuminable Display Device, of which the following is a specification, reference being had to the accompanying drawing forming part thereof.

In the drawing:

Fig. 1 is a side view of an illuminable display device, showing my new design;
Fig. 2 is a view of the opposite side; and
Fig. 3 is an end view thereof.

I claim:

The ornamental design for an illuminable display device, as shown.

FREDERICK CARL REINSHIELD.
